UNITED STATES PATENT OFFICE.

ALLAN J. GROSS, OF CHICAGO, ILLINOIS, ASSIGNOR OF TWO-THIRDS TO JOHN L. KENNEDY, OF CHICAGO, ILLINOIS.

AUTOMATIC SPRINKLER.

1,285,133.

Specification of Letters Patent. Patented Nov. 19, 1918.

Application filed February 23, 1915. Serial No. 10,067.

To all whom it may concern:

Be it known that I, ALLAN J. GROSS, a citizen of the United States, residing at Chicago, in the county of Cook and State of Illinois, have invented certain new and useful Improvements in Automatic Sprinklers, of which the following is a description.

My invention belongs to that general class of devices known as automatic sprinklers, and relates particularly to a sprinkler head for automatic sprinkling systems. The invention has among its objects the production of a device of the kind described that is simple, convenient, compact, durable, efficient and satisfactory. It has particularly among its objects the production of an improved mechanism for securely and positively maintaining the valve upon its seat, and which construction will preclude the possibility of dead centering or toggling. In the improved construction shown the mechanism is locked against operation by a fusible link, or what might be properly termed a fusible link key, the various parts being so constructed and the leverage so compounded that a very small percentage of the strain or power applied to the levers is transmitted to the fusible solder of the link or key. The invention also has among its objects the production of a device that is exceedingly sensitive upon the melting of the fusible retainer, for securing the parts of the key together, but which is flexible enough so as not to be operative upon abnormal shocks, nor which will be rendered inoperative by an incomplete opening of the sprinkler, and cooling and resetting of the solder by spray. The invention in one form shown also embodies an improved deflector designed to distribute the water in an efficient manner, but without the necessity of overlapping the spaces in order not to leave any unprotected. Other objects and advantages of the construction will appear and be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts,

Figure 1 is a side elevation of one form 55 of my improved sprinkler head;

Fig. 2 is a top plan view of the same;

Fig. 3 is a sectional view taken substantially on line 3, 3 of Fig. 1;

Fig. 4 is a sectional view taken substantially on line 4, 4 of Fig. 1;

Fig. 5 is a perspective view of one of the strut members;

Fig. 6 is a similar view of the other coöperating member; 65

Fig. 7 is a perspective view of one part of the link or key members;

Fig. 8 is a similar view of the coöperating member;

Fig. 9 is a side elevation of another form 70 of my device;

Fig. 10 is a top elevation of the same;

Fig. 11 is a sectional view of the same taken substantially on line 11, 11 of Figs. 9 and 12. 75

Fig. 12 is a sectional view through the same similar to Fig. 4;

Fig. 13 is a perspective view of one of the strut members;

Fig. 14 is a similar view of the other member; 80

Figs. 15 and 16 are perspective views of the coöperating link or key members;

Fig. 17 is a partial side elevation and sectional view of a head illustrating a slightly 85 different construction of strut members;

Fig. 18 is a sectional view taken substantially on line 18, 18 of Fig. 19, of a simplified strut and key member;

Fig. 19 is a view in elevation of the same; 90

Fig. 20 is a sectional view taken substantially on line 20, 20 of Fig. 21, illustrating another construction of strut and key, and

Fig. 21 is a view in elevation of the same.

Referring to the drawings, in which my device is shown, Figs. 1 to 8 illustrate one form of the complete head. Referring to these figures, 1 is the body of the head or portion of the frame, which is formed as at 5, or in an equivalent manner for attachment to the water supply. The frame is formed with the arms 2, the ends of which

are connected by a boss 3, through which extends a screw member 6, the head 7 of which is shown in Fig. 2. The part 1 is chambered in the usual manner, the outlet or discharge opening being normally closed by a suitable valve member 4, arranged to seat on the part 1. I have shown a gasket 10 arranged between the valve and its seat, the particular construction of the valve and seat being as preferred. The valve, as clearly shown in Fig. 4, is formed with a depression 8, and the adjustable screw member 6 with the recess or depression 9. Arranged between the adjustable member 6 and the valve 4 is a strut or retaining member, which consists of the coöperating parts 11 and 16. Part 11 (see Fig. 6) is formed as at 12, or in an equivalent manner to seat in the depression 8 in the valve 4, and is offset at 13, and formed with a shoulder 14, the same being substantially L-shaped. The opposite end 15 is preferably beveled, as shown, or that is brought substantially to a knife edge, although somewhat blunt. The other member or part 16 is formed with a projection or extension 17 at one end, and with a part 18 arranged to seat in the recess 9, of the member 6. It is formed with an offset or projection 20, shouldered at 21, so that it is substantially T-shaped. In operation the struts or parts 11 and 16 form substantially a single strut, as most clearly shown in Fig. 4. Referring to this figure, it will be noted that the end 15 of part 11 engages in shoulder 19 of part 16, the engagement being off center, so that as the screw 6 is adjusted or screwed down, the tendency for the lower end of part 16 is to be moved away from 11, thereby releasing the part 11 and valve 4.

The parts are maintained in operative position by what may be termed a fusible link or key, which consists of suitably formed parts 22 and 27, secured together by fusible solder 33, or its equivalent. The part 22, which is most clearly shown in Fig. 8, is formed with an offset at 23, with its lower end 24 arranged to rest upon the extension 13 of strut part 11, and be engaged by the shoulder 14. The same is prevented from sliding sidewise by the ears 25. I have also shown a part 26 offset laterally at one side, the purpose of the same being more fully described hereafter.

The coöperating part 27 is formed at 29 to engage shoulder 21 on extension 20 of part 16, the ears 30 normally maintaining the part against sidewise movement. As shown, the same is offset as at 28, the lower end being formed with ears 32. The part is positioned with its face against the face of part 22, as shown in Fig. 4, with the ears 32 at the sides of the offset 26. The link or key parts are then secured together by solder 33, or in an equivalent manner. The exten-

sion 26 forms a convenient surface for the solder to engage, and the solder passes through the opening or cut-out and engages on both sides of part 22, as clearly indicated in Fig. 4. It will be noted, as shown in the figure just referred to, that the lower end of strut part 16 rests against the fusible link or key substantially at the offset 23, but otherwise the key is only in contact with the parts at the extensions 13 and 20. Assuming the parts are assembled as shown in Fig. 4, if the adjustable spindle or screw member 6 is turned down, movement is transmitted through the strut members on the valve 4. The key or link, however, retains the strut part 16 and prevents any turning movement. The degree of temperature at which the key will release the struts, of course, depends upon the composition of the fusible solder retaining the key in place. Notwithstanding the fact that a great strain may be placed upon the strut, but a small strain is placed upon or transmitted to the link, and, in fact, the strain is so slight that even sealing wax is sufficient to retain the link or key parts together.

However, upon failure of the fusible retainer 23, the leverage is sufficient to violently throw the link parts out of operative position, and the struts as well. Upon the releasing of the struts, the valve 4 is, of course, released, permitting the water to escape. A baffle 34 is shown carried by the frame for distributing the water, the same being slotted at 35, permitting the water to reach the ceiling.

The construction shown in Figs. 9 to 16 inclusive is somewhat similar. For illustration I have shown the same type of frame and adjusting screw, and a similar but slightly different form of valve 38. In this case the valve 38, which is seated on a gasket or packing ring 41, is formed with a slot or recess 39, and with an additional slot or recess 40. Broadly speaking, the construction of struts and key is the same except that the key is arranged to engage the valve in slot 40 instead of an extension upon the valve strut member. As shown, strut member 42 is formed with its ends as at 43 and 44, part 45 being similar to part 16. It has the end 47 formed with a shoulder 48 at one side, and shoulder 51 in the extension 50, together with boss 49, the lower end 46 being arranged to bear against the key. In this case, however, the part 52 of the key is arranged to rest in the groove 40, the same being offset as at 53 and formed with a cut-out and extension 54. The coöperating part 57 is offset at 58, and formed at the ends as at 59 and 61, similar to part 27. The parts are secured together by solder 63, or the equivalent. The operation is substantially identical with the other construction pre-

viously described. I have shown the frame equipped in this case with a square baffle having the edges flanged or turned down at the desired angle and slotted as at 56. The 5 purpose of this type of baffle is to so distribute the water that the water from the sprinklers will not overlap. In laying out a system it is customary to lay off the spaces protected by sprinklers into a series of 10 squares, but owing to the distribution being circular to fully cover protected areas, the distribution from several sprinklers must overlap, thereby giving more water than necessary. This type of baffle is intended 15 to distribute the water in accordance with the lay-out.

In the construction shown on Fig. 17, the strut 65 is identical with strut 42 shown in Fig. 14. The strut part 66, however, is 20 formed with an extension or pin 67, or its equivalent, arranged to be engaged by an extension 69 on the key part 68. The co-operating key part 71 is arranged at its end 72 to engage in the slot in the valve 38. It is 25 also provided with ears 73, adapted to maintain the parts in proper relation with each other. In this case the solder 74 may be arranged substantially as shown. While I have shown the key in Figs. 12 and 17 as 30 engaging the cap or valve, obviously the parts might be reversed and the key engage with a suitable part arranged above the key and strut members, or the construction might be modified to be similarly arranged at both ends of the key.

A slightly modified construction of strut members and keys therefor is shown in Figs. 18 to 21. In the construction shown in Figs. 18 and 19, member 76 is formed as at 40 77 to engage with the valve, and member 80, as at 81, to engage in the adjustable screw, it being understood, however, that the parts may be reversed or inverted. Part 80 is extended as at 82 on one side with a shoulder 45 below, and formed with a shoulder 83 upon the side. Part 76 is arranged to engage at its end 78 with the shoulder 83, and is provided with an extension 79, having a shoulder against which the lower end of the 50 key member may bear. The key 84 is secured to part 80 by fusible solder 85, or the equivalent. I have shown the part 80 and key 84 formed, with a hole 86 and slot 87, so that the solder may flow through and 55 have a secure hold. With this construction I preferably form a bead or lip 88 on the part 80, which bears against the key 84, so that the parts are in contact at substantially that point, and at the upper end of the key.

60 The operation is obvious from the previous descriptions of the other forms.

In the form shown in Figs. 20 and 21, the strut members are very similar to those previously described, and the key also re-

sembles keys previously described. Referring to these figures, strut member 90 is formed with a part 92 arranged to engage with one of the head parts for such valve, and with an extension 93 having a shoulder 94 formed thereat. The upper end 95 is arranged to bear against shoulder 97 on part 91, which part is formed as at 96 to engage one of the sprinkler head parts, as for example the adjusting screw, also extended as at 98 and formed with a shoulder 99. The 70 key consists of two parts 101 and 105. Part 101 is offset at 102 with the end 103 in engagement with the shoulder 99, and ears 104 maintaining the parts in operative positions. Part 105 is offset as at 106 with the end 107 75 in engagement with shoulder 94, and ears 108 engaging on each side of the extension. The parts are shown with holes or openings 109, 110 therethrough, and secured together by solder 111, or the equivalent. The solder 80 may also be placed at 112 and 113, if so desired. The part 91 is also formed with a body 100, so as to form a minimum bearing on the key. The operation is as previously set forth.

The parts are preferably made of corrosion proof bronze, the same being so designed as to give the greatest strength for the given amount of metal, and to resist deformation when under normal strain, as applied to the closure by means of the compression screw. It should be particularly noted that there is no direct tension or compression on the fusible link or key, but only the strain due to the turning tendency of 90 the strut members, which carry the load due to the compression of the screw member. There is therefore no tendency of the parts of the key to creep or the fusible solder to flow. It will be noted that the strut levers 100 or members are constructed in such manner as to preclude the possibility of dead centering or toggling, the leverage being so compounded that there is but small strain on the key. The key or fusible link is extremely sensitive, the complete construction being such as to cause the parts to separate all parts of the closing device upon melting of the fusible solder. However, the parts are not affected by abnormal shocks, owing 105 to the flexibility of the link or key and the struts. The action upon releasing of the solder due to the parts of the strut being under compression is such as to violently throw the parts clear of the sprinkler. The 110 complete opening of the sprinkler cannot be prevented by spray or cold water leaking from the nozzle before it is completely open and resetting the fusible solder while the separation of the locking members is incomplete. Also in the construction wherein the square or rectangular deflector is used the 115 water is distributed over an approximately 120 125

square area, each sprinkler covering its own allotted space without necessarily overlapping it, in order to leave no dry or unprotected spaces.

Having thus described my invention, it is obvious that various immaterial modifications may be made in the same without departing from the spirit of my invention; hence I do not wish to be understood as limiting myself to the exact form, construction, arrangement or combination of parts herein shown and described, or uses mentioned.

What I claim as new and desire to secure by Letters Patent is:—

1. A retaining device for sprinkler heads, comprising a pair of coöperating strut members, a key comprising two parts arranged to overlap and lie face to face, one part 20 formed with tongues at one end on each edge thereof and having a central portion partially cut out and offset toward the other, the other part formed with a tongue on each edge at each end.
2. A retaining device for sprinkler heads, comprising an L-shaped member, and a T-shaped member arranged with the head of the L-shaped member positioned under one side of the head of the T-shaped member, 30 with the leg of the T member extending substantially parallel with the leg of the L member, a key comprising two parts arranged face to face, fusible means for securing said key parts together, said key positioned with one end in engagement with the base of the L member, and the other end in engagement with the under side of the head of the T member on the opposite side of the leg thereof.
3. In a sprinkler head provided with a suitable valve, means for securing said valve in operative position, comprising two parts overlapping each other, one part formed with a shoulder, the other part tapered to 45 one edge and arranged to engage the other part with the edge at said shoulder, each of said parts provided with an extended part, a key extending between said extended parts and contacting with the free ends of said 50 extended parts, said key comprising a plurality of parts, and fusible means for securing said parts together.
4. A retaining device for sprinkler heads comprising a pair of coöperating strut members, a key lying substantially parallel with said strut members, one of said strut members engaging said key member at a point adjacent one end and at a second point intermediate its ends on the opposite side 60 thereof, and fusible means for retaining said key in operative locking position.
5. A retaining device for sprinkler head valves, comprising a pair of coöperating strut members, a key comprising two parts

arranged to overlap and lie face to face substantially parallel with the strut members and in engagement therewith adjacent the ends of the key, one of said members arranged to engage the key at a point intermediate its ends, and fusible means for retaining said key parts in operative locking position. 65

6. A retaining device for sprinkler head valves comprising a pair of coöperating overlapping strut members arranged to engage each other and the valve and the sprinkler head frame, a two part key arranged to engage the strut members at one side adjacent each end, one of said strut members arranged to engage said key on the 70 opposite side intermediate the ends, and fusible means for securing the parts of said key together. 75

7. In a sprinkler head consisting of a suitable frame and having a valve, a two part strut arranged at its ends to engage said valve and said frame, one strut member having a shoulder formed therein and overlapping the other, and the other constructed at one end to engage the first at 80 said shoulder, a key for maintaining said strut parts in operative position including fusible retaining means, one strut member arranged to engage the key adjacent one end at one face thereof and the other arranged 85 to engage the key at said face adjacent the other end, and at a point intermediate the ends on the other face. 90

8. In a sprinkler head provided with a valve opening and with an adjustable member 100 arranged in alinement therewith, a strut arranged between said member and the valve member, said strut comprising two parts, one part arranged to engage the valve and the other said adjustable member, 105 said parts in engagement with each other at one side of a line extending between the points of their engagement with said parts, whereby when pressure is applied on the end of the part engaging said valve one part 110 will have a turning movement about the end of the other, and means for preventing said movement consisting of a key comprising a plurality of parts arranged at one side of the strut and engaging the same substantially adjacent the ends of the struts and key, and at a point between said ends, and fusible means for securing said key parts together. 115

9. In a sprinkler head valve retaining device of the kind described and in combination, a pair of coöperating strut members arranged to engage the valve and a portion of the sprinkler head frame, a key consisting of a plurality of parts provided with 120 fusible means for retaining the parts together, one strut member provided with an offset portion arranged to engage said key 125

at one side thereof adjacent one end, and the other part provided with a similar offset portion arranged to engage said key at the adjacent end on said side, and provided with an extending part arranged to engage the key at a point between the ends but on the opposite side thereof.

In testimony whereof, I have hereunto signed my name in the presence of two subscribing witnesses.

ALLAN J. GROSS.
